DUAL-MODE BIFURCATED WAVEGUIDE TRANSDUCER

Charles W. Curtis, Manhattan Beach, and Robert L. Fogel, Torrance, Calif., assignors to Hughes Aircraft Company, Culver City, Calif., a corporation of Delaware

Application October 1, 1956, Serial No. 613,023

3 Claims. (Cl. 333—9)

This invention relates to a waveguide transducer and more particularly to a waveguide structure which permits the selection of predetermined modes.

In wave energy transmission systems it is often desirable to provide for propagation of more than one signal using a common frequency by utilizing various wave energy modes as separate channels. It is well known in the art that two dominant modes such as the TE_{01} - and the TE_{10} -mode of the square waveguide will propagate independently because they are orthogonal. The practical problem associated with this problem is to excite or to extract wave energy in one mode independent of the other mode. One transducer having the above indicated properties which has been used in the past to perform this function comprises a circular waveguide to which two rectangular waveguides are radially coupled by way of apertures. The longitudinal axes of the two rectangular and the circular waveguides are mutually perpendicular. This waveguide transducer which is fully described in "A Broad-Band Dual-Mode Circular Waveguide Transducer" by R. D. Tompkins, IRE Transaction on Microwave Theory and Techniques, published by the Institute of Radio Engineers, Inc., vol. MIT-4, number 3, page 181 (July 1956), involves the transformation of orthogonal TE_{11} -modes of the circular waveguide to the dominant TE_{01} -modes of two separate and orthogonally positioned rectangular waveguides. This, as well as other prior art transducers, give rise to relatively high reflections due to the non-symmetry of the junctions and less isolation between the channels than desirable. Further, this type of transducer requires the excitation of an aperture, namely, the rectangular opening in the circular waveguide wall to which the rectangular waveguide is coupled. All systems, which necessitate aperture excitation, have inherent limitations as to power handling capacity and broad-banding. The prior art transducers of the type here considered have been made more useful by the inclusion of conductive posts, resistance cards, matching stubs and other similar aids. However, requirements for increasing power handling capacity, broad-band properties, and the degree of isolation between the channels often conflict so that optimizing one property is done at the expense of some other property of the transducer.

It is therefore an object of this invention to provide a waveguide transducer adapted to independently excite or extract wave energy in two orthogonal modes without the use of auxiliary matching or absorption components or the inclusion of electrical short circuit terminations.

It is a further object of this invention to provide a symmetric waveguide transducer having negligible reflection loss, a high order of isolation, and which is capable of handling large amounts of power, both when exciting and when extracting one of the modes.

It is a still further object of this invention to provide a waveguide transducer which is simple in construction, has a high efficiency, and which is broad-band in operation.

In accordance with the dual-mode waveguide trans-

2

ducer of this invention, a cruciform waveguide adapted to propagate the two orthogonal TE_{10} and TE_{01} wave energy modes may be bifurcated into two rectangular waveguides each adapted to propagate a different one of the two orthogonal wave energy modes. This transducer is a device which along one direction of propagation separates two orthogonal wave energy modes, and along the other direction of propagation combines two orthogonal wave energy modes.

Fig. 1 is a perspective end view of the bifurcated waveguide transition of this invention, Fig. 1a shows the electric field vector distribution thereof;

Fig. 2 is a cutaway perspective side view of the waveguide transducer of Fig. 1; and

Fig. 3 is a cross-sectional view taken along the line 3—3 of the waveguide transducer of Fig. 2.

The novel features which are believed to be characteristic of the invention, both as to its organization and method of operation, together with further objects and advantages thereof, will be better understood from the following description considered in connection with the accompanying drawing in which an embodiment of the invention is illustrated by way of example. It is to be expressly understood, however, that the drawing is for the purpose of illustration and description only, and is not intended as a definition of the limits of the invention.

Referring now to the drawing wherein like numerals are used throughout to designate like parts, there are shown different views of the dual-mode bifurcated waveguide transducer in accordance with this invention. A first rectangular waveguide 10 having a longitudinal axis 12 is curved along its direction of elongation about its broad walls 14 and 16. A second rectangular waveguide 20 having longitudinal axis 22 is curved along its direction of elongation about its narrow walls 24 and 26. The first and the second waveguides 10 and 20 are brought into coincidence with one another by removing obstructing interfaces between them so that the longitudinal axes 12 and 22, which define a plane, eventually merge with one another at the point 28.

As can be seen from the drawing, the waveguide structure there shown is one in which one curved rectangular waveguide intersects with, merges into and combines with another curved rectangular waveguide. At the point 28 the curved portions of the first and the second waveguides 10 and 20 terminate and a straight portion commences.

45 The waveguides 10 and 20 may therefore be regarded as having lost their identity as individual waveguides and instead define a cruciform waveguide 30 having longitudinal axis 32.

Whereas from a structural point of view the waveguide transducer of this invention may be regarded as a combination of two intersecting rectangular waveguides, it is nevertheless useful to describe the waveguide structure from a functional viewpoint. From a functional viewpoint, the invention comprises a cruciform waveguide 30 which is bifurcated into two rectangular waveguides 10 and 20 which are spatially disposed with respect to one another so that the narrow walls of one are parallel to the broad walls of the other, and whose longitudinal axes 12 and 22 define a plane.

Fig. 1a depicts the orthogonal modes which the cruciform waveguide 30 is adapted to propagate. These are respectively similar to the TE_{10} -mode and the TE_{01} -mode of the square waveguide. This nomenclature indicates the orthogonal nature of the two modes but otherwise is not helpful after the wave energy propagated through the cruciform waveguide 30 passes point 28 in the transducer at which bifurcation into the two rectangular waveguides 10 and 20 commences. The wave energy in the two modes will separate after passing point 28 so that the

first and the second waveguide 10 and 20 each are excited in their respective dominant mode.

The symmetry of the wave energy transducer of this invention which results by the bifurcation prevents any cross coupling between the modes and therefore assures of a high degree of isolation. Further, the two rectangular waveguides are excited directly, in contradistinction from aperture excitation, which provides for better broad band operation and large power handling capacity.

The applications which involve the employment of the dual-mode bifurcated waveguide transducer of this invention are very numerous as is immediately apparent to those skilled in the art. Generally, the cruciform waveguide is coupled by standard techniques such as a quarter wave transformer or a tapered section to a waveguide of more conventional cross-section and adapted to propagate orthogonal waveguide modes. Such conventional cross-sections of course are square or circular.

One application of the bifurcated transducer utilizes the property that orthogonal modes may be transmitted along a square or circular waveguide independent of one another. It is therefore possible to effect the excitation and the subsequent transmission of independent wave energy signals along a single square or circular waveguide. Each of the two independent signals is excited in one or the other of the rectangular waveguides 10 and 20. The two signals will then be propagated in the cruciform waveguide 30 as orthogonal modes. To separate the two signals, a second bifurcated wave energy transducer may be coupled to the transmission system having corresponding rectangular waveguides either parallel or perpendicular to the first transducer.

Another application of this bifurcated waveguide transducer involves conventional duplexing. Here the cruciform waveguide is coupled to a 45 degree rotator such as an isolator employing a ferromagnetic ceramic element which is subjected to a longitudinal constant magnetic field. Such isolators are well known in the art. The combination of the bifurcated transducer and the isolator provide duplexing action when one rectangular waveguide is coupled to a transmitter, the second waveguide is coupled to a receiver and the output of the isolator is coupled to an antenna.

Still another application of the bifurcated wave energy transducer of this invention is the excitation of a wave energy antenna. Such excitation modes include circular polarization, elliptical polarization or plane polarization along one or two predetermined planes depending on the respective amplitude and phase excitation of the first and second waveguide.

What is claimed is:

1. A dual-mode bifurcated waveguide transducer comprising: a first rectangular waveguide including parallel broad walls curved along its direction of elongation about said broad walls and terminating in a first straight portion, said first waveguide defining a first longitudinal axis; and a second rectangular waveguide including parallel

narrow walls curved along its direction of elongation about said narrow walls and terminating in a second straight portion, said second waveguide defining a second longitudinal axis, said first and said second waveguides being spatially oriented with respect to one another so that the broad walls of said first waveguide are parallel to the narrow walls of said second waveguide, and coupled to one another by progressively increasing intersection so that said first straight portion and said second straight portion combine to provide a cruciform waveguide having a third longitudinal axis lying in a plane defined by said first and said second longitudinal axes and coinciding therewith along said straight portion.

2. A waveguide transducer for coupling energy between a common waveguide section and two individual waveguide arms, the modes supported in each of the different individual arms and in the common section being orthogonal with respect to each other, said transducer comprising: a first curved rectangular waveguide having planar broad walls and curved narrow walls; and a second rectangular waveguide having planar narrow walls and curved broad walls, the broad walls of the two waveguides lying in planes which are normal with respect to each other, said waveguides merging into a common cruciform rectangular waveguide body defining two rectangular waveguides normal to each other and colinear with each other, said waveguides being merged along the lines of intersection of the walls thereof and having matching internal apertures such that the interior of each waveguide is of at least full cross section and such that a central portion of each of said waveguides at the common cruciform body is common with the other of said waveguides.

3. A dual mode bifurcated waveguide transducer comprising: a first rectangular waveguide including parallel broad walls, curved along its direction of elongation about said broad walls, and terminating in a first straight rectangular waveguide portion; and a second rectangular waveguide including parallel narrow walls, curved along its direction of elongation about said narrow walls, and terminating in a second straight portion, the planes of the broad walls of said first and second waveguides being normal with respect to each other and the directions of curvature of the curved walls therein being opposite in direction, the straight portions of each of said waveguides being colinear, the bodies of said waveguides merging into each other so that a common cruciform waveguide body is provided by the straight sections of said rectangular waveguides.
